Inventor:

Samuel P. Bartley
 By his Atty A. H. Evans

United States Patent Office.

SAMUEL P. BARTLEY, OF COLUMBUS, OHIO.

Letters Patent No. 76,585, dated April 14, 1868.

IMPROVEMENT IN STEAM-BOILER FURNACES.

The Schedule referred to in these Letters Patent and making part of the same.

TO ALL WHOM IT MAY CONCERN:

Be it known that I, SAMUEL P. BARTLEY, of Columbus, Ohio, have invented a new and useful Improvement on the Construction of a Steam-Boiler; and I do hereby declare that the following is a full, clear, and exact description of the construction and operation of the same, reference being had to the annexed drawings, making a part of this specification, in which—

Figure I is a side view.

Figure II is a top view without the boiler.

Figure III is a longitudinal section through the centre.

Figure IV is a cross-section, and

Figure V is a front view of the boiler.

The nature of my improvement consists in a funnel, to shape the flames to the boiler; also a chamber, so constructed as to guide the flame to the rear, and into the flues of the boiler, and furnished with air, to promote the combustion of the smoke and gases, which would otherwise pass out without burning.

To enable others skilled in the art to make and use my invention, I will proceed to describe its construction and operation.

The brick-work A, Fig. I, on which rests the boiler, is constructed as in ordinary cases, except that I introduce the cold-air pipe E, which admits the cold air into the chamber O, Fig. III. The funnel-shaped chamber or passage D is so constructed as to force the flames directly against and around the boiler, while the large chamber O is curved at the rear end, as shown in Fig. III, which curve gives motion to and directs the flame into the flues of the boiler. The cold-air pipe E passes square through the walls of the furnace, and then takes the same circle with the chamber D, with a slot running the whole length of the pipe, which is to be placed immediately in rear of and flush with the funnel-shaped chamber D. It is confidently believed and claimed that this arrangement will save fifty per cent. of the fuel generally used in the ordinary furnaces for heating boilers.

The cold-air pipe E may be introduced under the flues, or at other points, without departing from the spirit of my invention.

What I claim as my invention, and desire to secure by Letters Patent, is—

The funnel-shaped chamber or passage D, in combination with circular or curve in rear of chamber O, and the cold-air pipe E, constructed and operating substantially as and for the purpose described.

SAMUEL P. BARTLEY.
